AUTOMATIC GAUGE CONTROL

Thomas H. Bloodworth, Elm Grove, Wis., assignor to Allis-Chalmers Manufacturing Company, Milwaukee, Wis.

Filed Oct. 24, 1960, Ser. No. 64,520

3 Claims. (Cl. 89—35)

This invention relates to an automatic gauge control for a rolling mill. The control is particularly intended for a hot strip rolling mill.

The problem of obtaining accurate gauge control in a rolling mill has become more and more difficult as mill speeds increase. At the same time customers have demanded that metals have more uniform gauge. The gauge of the product of a rolling mill depends in part on the tension on the material in the mill and on the pressure of the work rolls on the material. In addition, the hardness and the thickness of the material entering the mill influence the gauge. Automatic gauge controls have been suggested for hot strip mills in order to improve the uniformity of the metal as it enters the cold mill. An automatic gauge control for a hot strip mill presents problems that do not exist in the automatic gauge controls for cold mills. In a hot mill, water cooled metal skids which support the metal while it is being heated prevent the metal from heating uniformly. Also, the strip cools somewhat before it enters the mill, and the last portions to enter the mill are appreciably cooler and harder than the first portions. These and other variations in temperature and thickness may cause the mill to roll the strip off gauge.

The prior art has suggested automatically varying the roll pressure to produce the effect to a "stiff mill." In a stiff mill the spacing between the work rolls does not change even though the pressure on the work rolls changes as the temperature or the thickness of the strip entering the mill changes. Analyzing some of the factors that influence gauge suggests that each stand of a stiff mill would roll uniform gauge and that the interstand tensions would remain constant. However, many of the factors that influence gauge have not yet been systematically analyzed, and the concept of a stiff mill is not a completely satisfactory basis for an automatic gauge control.

It would be highly desirable to maintain constant interstand tension. Changes in strip tension tend to transmit the effects of a change in roll pressure at one reducing stand to the other stands. If the interstand tension is nearly constant, the strip can be rolled at a lower tension than if the interstand tension varies widely. However, controls of the known prior art have not maintained constant tension but usually have varied the interstand tension to regulate the strip thickness. Other prior art mills have varied the work roll pressure only in a narrow range and in this way have kept the tension variations within an acceptable range.

The automatic gauge control of this invention senses the interstand strip tension and the error in strip thickness. When the material is off gauge, the control changes the roll pressure to correct the gauge. The control varies the speeds of the work rolls to maintain constant interstand tensions. The constant tension regulators isolate the effects of work roll changes at each stand. Under most rolling conditions the constant tension control permits the work roll pressure to be varied over a very wide range. However, under other conditions, wide variations in work roll pressure may increase the strip tension more than the drive motors can compensate for. The strip tension would then vary with roll pressure just as in a mill without this control. Excessive tension is highly undesirable because it tends to reduce the strip width as well as the strip thickness. In addition, excessive tension may cause the work

2

rolls to slip, or it may break the strip. The tension sensing components of this control prevent the roll pressure from increasing or decreasing if the mill stand drive motors would be unable to offset the resulting change in tension.

5 The roll pressure limit feature of the control further increases the range that the work roll pressure can be varied under most conditions, and it thereby simplifies adapting the control to a number of stands.

One object of this invention is to provide a new and 10 improved automatic gauge control.

Another object of this invention is to provide a new and 15 improved automatic gauge control that is particularly suited for a hot strip mill.

Another object of this invention is to provide a new and 20 improved automatic gauge control that maintains constant interstand tension and varies the work roll pressure over a wide range.

Another object of this invention is to provide a new and 25 improved automatic gauge control in which work roll pressure controls are used on several reducing stands independently, and interstand tension regulators isolate the effects of changes in roll pressure and roll spacing at each stand.

Other objects and advantages will appear from the drawing and from the following description of the invention.

25 In the drawing, FIG. 1 schematically illustrates an embodiment of the control of this invention in combination with a hot strip mill. Solid lined arrows indicate the flow of information and orders between elements of the control and the mill.

30 FIG. 2 schematically illustrates one of the components of the control of FIG. 1.

FIG. 1 shows the automatic gauge control of this invention with a well known five stand hot strip mill. Elements of the mill and the control that are duplicated at 35 several stands have a common number and in some cases are distinguished by letter suffixes. Each stand 1, 2, 3, 4 and 5 has a pair of work rolls 11 and 12 and a pair of backup rolls 14 and 15 that a strip of metal 16 passes between. A screw device 18 and a cooperating screw motor 40 force the work rolls together against the strip, and direct current motors 21 rotate the work rolls through drive shafts 23 to pull the strip through the mill. The screw motors 19 are each energized and deenergized by an 45 electrical controller 24 that receives a signal from the automatic gauge control. Each controller 24 may comprise two magnetically operated switches that connect the motor 19 to a source of electrical power to run the motor in either direction to raise or to lower the screw 18. The coils of the operating magnets of the switches receive the 50 signal from the programmer 63. As each stand reduces the strip thickness, it increases the strip speed. The drive motors 21, except the drive motor 21b of the second stand, have speed controls 28 that operate on the motor field windings 29 in response to speed control orders from the 55 automatic gauge control. The second stand is the pacer stand, and its motor 21b is set to the desired speed by suitable means that is illustrated schematically by a field control rheostat 30. The motors 21a, c, d, e, of the other mill stands are set up to run at differing speeds that correspond 60 to the speed of the motor 21b of the second stand and the reduction in strip thickness between stand two and the other stands. The control varies the motor speeds as necessary to maintain constant interstand tension. Each speed control means comprises a magnetic amplifier 31 that receives and amplifies an input signal from the control and an exciter generator 32 that further amplifies the 65 signal and energizes the field winding 29 of the motor 21.

Loopers 41, 43, 44 and 45 are positioned between the stands to help maintain the desired interstand tension. A 70 looper comprises a roller 47 and a member 48 that pivots about a support 49 and holds the roller against the underneath side of the strip 16. A looper motor 50 applies

torque to the looper support through a shaft 51 and tends to raise the strip where it passes over the roller. When the interstand tension decreases, the looper raises the strip further and tends to prevent slack in the strip. When the interstand tension increases, the strip forces the looper down and lessens the tension increase.

The specific features of the mill of the drawing illustrate general features that are found in many mills that might use this control. When the control itself is understood, it will be apparent that various well known mill components may be substituted for the components that are illustrated.

The automatic gauge control can be understood more easily by first considering the operation of the mill without a control. When the mill is set up for the desired gauge, the work rolls 11, 12 of each stand are properly spaced apart to obtain the desired reduction for the expected thickness and hardness of the entering strip 16, and the speeds of the work roll drive motors 21 are set to correspond to the desired reduction. So long as the strip is the proper hardness and thickness, the mill produces nearly uniform gauge. However, when a harder portion of the strip enters the first stand, the work rolls spring apart slightly. Consequently, the exit gauge increases, the strip exit speed decreases in proportion to the increase in gauge, and the tension increases between stands one and two. When the tension increases between stands 1 and 2, but before the harder portion of the strip reaches the second stand, the second stand rolls the strip thinner than is desired. When the harder portion of the strip enters the second stand, a similar effect occurs between stands 2 and 3. In addition, the strip tension increases between stands 1 and 2 and causes the first stand to roll the strip thinner than desired. When the strip enters the first stand too thick, the first stand rolls the strip thicker than desired. In addition, the strip tension between stands one and two decreases and the second stand tends to roll the strip too thick even before the thicker portion of the strip enters the second stand. In automatic gauge controls of the prior art, changes in strip tension tend to transmit the effects of roll pressure adjustments from stand to stand. The changes in strip tension have limited the range of roll pressure adjustments in these prior art controls.

The automatic gauge control of this invention operates on the motor speed controls and on the screws in response to changes in strip thickness and changes in interstand tension. There are several well known devices that measure tension and thickness. The drawing illustrates X-ray thickness gauges 52, 53 and looper following tension gauges 59.

One thickness gauge 52 is located at the exit side of the first stand, and the other thickness gauge 53 is located at the exit side of the last stand. The gauges 52, 53 may be located at other stands if desired so long as each gauge measures the product of a group of one or more of the mill stands. The gauges 52, 53 each comprise a radiation source 55 that is positioned on one side of the strip 16 and a radiation receiver 56 that is positioned opposite the source on the other side of the strip. The strip 16 absorbs the radiation in proportion to the strip thickness, and the receivers 56 produce electrical signals 57, 58 that indicate strip thickness as a function of the proportion of the radiation that penetrates the strip.

The position of a looper 41 indicates the interstand tension. As the roller 47 and the strip 16 rise, the force of the strip on the roller increases and the force of the looper motor 59 on the roller decreases trigonometrically. Similarly, as the roller and the strip fall, the downward force of the strip decreases and the upward force of the looper motor increases trigonometrically. Thus, there is a determinable stable position of the looper for every value of strip tension. A magnetic reluctance device 59 is coupled to the looper by a shaft 60 to follow the looper position. The reluctance device 59 produces a tension error signal

61 and a tension limit signal 62. The reluctance device may comprise a magnetic core that has a stationary member with an air gap and a movable member that varies the length of the air gap. The movable member, which is connected to the shaft 60, changes the reluctance of the core as the looper 41 turns the shaft 60. Coils on the core produce an electrical signal that varies with the reluctance of the core and thus with the tension of the strip 16.

10 Each reluctance device 59 feeds a tension error signal 61 into the amplifier 31 of its associated mill stand motor speed control 28. The speed control 28 adjusts the work roll speed in response to tension signal 61 to maintain the proper strip tension. The exciter 28a of the first mill stand motor speeds up the motor 21a when the tension is high between stands 1 and the pacer stand 2, and it slows the motor 21a when the tension is low. The mill stand motors 21c, d and e of stands 3, 4 and 5 have the opposite speed-tension relationship to the pacer stand 2, and the controls of these motors respond to tension errors in the reverse sense to the first stand 1. For example, when the tension rises between stands 2 and 3, the looper follower 59c orders the motor 21c to slow.

20 When the thickness gauge 52 senses a thickness error, it is desirable to operate the screw motor 19a of stand 1 for an increment that is proportional to the thickness error and then to deenergize the screw motor long enough for the corrected portion of the strip 16 to reach the thickness gauge 52. The control then orders an additional change in the roll pressure if this is necessary. The control for the first stand includes a programmer 63a, shown in detail in FIG. 2, that combines the thickness error signal 57 with other information and orders appropriate changes in the work roll pressure. One well known circuit that is suitable for programming the incremental changes compares an error with the rate that the system is changing in order to correct the error. The screws 18 have suitable means that provide an electrical signal that indicates the screw position. For example, the position indicator may comprise a synchro transmitter mechanically connected to rotate with the screw 18 and electrically connected to drive a synchro receiver in the programmer 65, and the synchro receiver may convert the screw rotation information to an analogous electrical quantity by positioning the slider of a potentiometer. The screws 18 feed back to the programmer a screw position signal 65 which indicates the rate that the mill stand is responding to the control. When the rate of correction of the screw position signal 65 reaches a predetermined balance with the thickness error signal 57, the circuit orders the controller 24 to deenergize the screw motor 19a.

30 In FIG. 2 the means for energizing the controller 24 in response to a balance between a thickness error and the rate of operating to correct the error is illustrated as an adder 66 that is connected to compare thickness error signal 57 and a rate signal 67 and to produce an output that is a function of their difference. Rate signal 67 is derived from screw position signal 65a by means 68 such as a differentiating device illustrated schematically by a capacitor-resistor differentiating circuit. Adder 66 may comprise means such as an amplifier having two inputs connected to add together. An AND gate 69 is connected to receive the output of adder 66 (and other signals) and to produce a two condition output signal to turn controller 24 either on or off.

40 The screw motor 19a is deenergized long enough for the corrected portion of the strip to reach the thickness gauge 52. Strip speed indicators 70 are coupled to the strip 16 through the driveshafts 23 or other suitable means. The strip speed indicator 70 produces a strip speed signal 72 that is fed into the programmer 63. After each incremental operation of the screws 18a, the programmer 63a orders the controller 24a to deenergize the screw motor 19a for a time that is inversely proportional to strip speed signal 72. At the end of this time the pro-

grammer receives a thickness signal 57 that indicates the effect of the last screw operation. In a typical situation the gauge error would be smaller than before, and the programmer 63a would order a shorter incremental screw change.

FIG. 2 illustrates the means for giving screw motor 19a an incremental adjustably timed operation as an adjustable timer 75 that is connected to receive a strip speed signal 72 and to receive a turn on pulse (produced by means represented schematically by capacitor 76) when controller 24 is turned off. When timer 75 is turned on, it runs for a time established by strip speed signal 72, and as it runs it maintains an appropriate polarity at its output to keep AND gate 69 closed to prevent operating controller 24. In a digital control, timer 75 may comprise a counter connected to count a predetermined number of pulses in speed signal 72; since each pulse corresponds to a predetermined increment of strip length, a preset number of pulses corresponds to the travel of the corrected region of the strip from stand 1 to gauge 52.

When the work roll pressure changes at stand 1, the strip tension tends to increase or decrease between stands 1 and 2, and the tension gauge 41a orders the motor 21a to speed up or slow down. When the motor 21a is at the limit of its control, it is desirable to prevent the screw motor 19a from further changing the roll pressure since this would change the strip tension. In the control of this invention the motor 19a is limited selectively only when the motor 21a could not match the resulting strip speed change. At all other times the motor 19a is free to respond to gauge error signals 57 and to vary the roll pressure over a wide range. When the motor 21a fails to maintain the work roll speed in response to tension error signals 61, the strip tension changes between stands 1 and 2. The tension limit signal 62 then orders the programmer 63a to prevent further changes in roll pressure until the strip tension returns to the range that the motor 21a can control. As FIG. 2 illustrates the controller 63a tension limit signal 62 is connected to allow AND gate 69 to open when the tension is normal and to cause AND gate 69 to close when the tension reaches the predetermined limit.

The first reducing stand with the screw control that has just been described produces nearly constant gauge in spite of variations in the incoming strip. It is highly desirable to also control the roll pressure at the other reducing stands to improve the uniformity of the strip. The controls for stands 2, 3, 4 and 5 may be simplified by providing only the single thickness gauge 53 near the exit end of the mill, and in some cases the tension limit signal is unnecessary at these stands. The thickness gauge 53 produces a single thickness error order 57 that is fed into each of the programmers 63b, c, d, e of reducing stands 2 through 5. Programmers 63b, c, d, and e may be similar to the programmer of FIG. 2 except that they do not have the tension input 62. Since the control maintains constant interstand tension, the programmers can operate independently without regard to the effect that the roll pressure changes have on strip speed. As the strip speed changes with changes in the strip or in the roll pressure, the control changes the speeds of the roll motors

21a, c, d and e correspondingly to prevent changes in interstand tension. Isolating the effects of tension changes greatly simplifies applying wide range controls to each of the stands.

5 Although the control has been described in terms of a single embodiment, those skilled in the art will recognize various changes that can be made within the spirit of the invention and the scope of the claims.

What is claimed is:

1. In a control for a hot strip mill having a plurality of reducing stands with screws for positioning the work rolls of said stands with respect to a rolled strip and with variable speed motors for driving said work rolls, said control comprising means sensing errors in the thickness of said rolled strip and ordering error correcting changes in the pressure of said work rolls, means sensing variations in interstand strip tension and ordering roll drive motor speed changes to maintain constant interstand tension, and means responsive to an uncorrected variation in strip tension to prevent roll pressure changes in a direction to further increase the error in strip tension.
2. In an automatic gauge control for a hot strip mill having a plurality of reducing stands with means for positioning the work rolls of the stands with respect to a rolled strip and with variable speed motors for driving the work rolls, said control comprising means sensing errors in the thickness of the rolled strip and ordering thickness error correcting changes in the position of said work rolls, means sensing variations in strip tension and ordering roll drive motor speed changes to maintain constant interstand tension, and means operable when the motor of one of said stands reaches a limit of speed control to prevent roll pressure changes at said one stand in a direction to further increase the error in strip tension.
3. In an automatic gauge control for a hot strip mill having a plurality of reducing stands with means for positioning the work rolls of the stands with respect to a rolled strip and with variable speed motors for driving said work rolls, said automatic gauge control comprising means sensing errors in the thickness of the strip of rolled material and ordering error correcting changes in the pressure of said work rolls, means sensing variations in strip tension between adjacent stands and ordering changes in the speed of the roll drive motor of one of said adjacent stands to maintain constant interstand tension, and means operable in response to an uncorrected increase in strip tension between two of said stands to prevent roll pressure changes at one of said two stands in a direction to further increase the strip tension.
